CLAIM

The ornamental design for an ink paper pack, as shown and described.

DESCRIPTION

FIG. 1 is a front view of an ink paper pack showing our new design;

FIG. 2 is a rear view thereof;

FIG. 3 is a top plan view thereof;

FIG. 4 is a bottom plan view thereof;

FIG. 5 is a left side view thereof; and,

FIG. 6 is a perspective view thereof.

The broken lines are for purposes of illustration only and form no part of the claimed invention.
